UNITED STATES PATENT OFFICE.

FREDERICK P. MCINTOSH, OF EAST ORANGE, NEW JERSEY, ASSIGNOR TO NEW JERSEY PATENT COMPANY, OF WEST ORANGE, NEW JERSEY, A CORPORATION OF NEW JERSEY.

PHONOGRAPH RECORDER.

Application filed February 17, 1921. Serial No. 445,608.

To all whom it may concern:

Be it known that I, FREDERICK P. MCINTOSH, a subject of the King of Great Britain, and a resident of East Orange, Essex County, New Jersey, have invented certain new and useful Improvements in Phonograph Recorders, of which the following is a description.

My invention relates to phonograph recorders, and while not limited thereto, is particularly directed to phonograph recorders of the graphophone type, that is, those designed to cut a hill and dale as distinguished from a lateral or zig-zag record groove.

The principal object of my invention is to provide an improved recorder of this type which is of simple construction and which is more efficient in operation and more economical to manufacture than similar recorders now made.

More particularly described, my invention consists of a recorder comprising a diaphragm casing and sound-conveying tube which are of improved form and which are operatively associated in a novel and simple manner, and also in novel means for effectively maintaining such casing and tube in operative relation, and which enables them to be readily and quickly assembled and disassembled.

Other features of my invention reside in the combinations of elements and construction of parts hereinafter more fully described and claimed.

For a clearer understanding of my invention, attention is directed to the drawing accompanying and forming a part of this specification, and in which the single figure 40 is a view in side elevation, partly in section and partly broken away, of a phonograph recorder embodying my invention.

Referring to the drawing, reference character 1 represents the body of the recorder which is of usual form, being provided, as is customary, with a depending annulus or flange 2 to form the chamber 3 and with a central, upwardly extending cylindrical, hollow neck 4. Reference character 5 represents my improved diaphragm support or casing to which is suitably secured, as by brazing, the base of a U-shaped arm or yoke 6. The outer ends of the legs of the yoke are pivoted at 7, to the lower end of 55 an arm 8 depending from a lateral exten-

sion or lug 9 formed on the body 1, whereby the diaphragm casing is pivotally supported from the body 1. The lug 9 and the adjacent portion of the flange 2 of the body 1 are slotted as indicated at 10 to receive the arm 6 so as to provide for an increased movement of the diaphragm casing 5 about the pivot 7 toward the body 1. The legs of the U-shaped arm 6 are connected intermediate their ends by a screw or rod 11, which coacts with a horizontal rod 12 having threaded connection with the lower end portion of the depending arm 8, to limit the downward pivotal movement of the diaphragm casing 5 with respect to the body 1.

The diaphragm casing 5 is preferably formed of sheet metal and is provided with an annular depending flange 13 within which the diaphragm 14 is preferably removably mounted, as by means of a ring or gasket 15 formed of rubber or other yielding material and provided with parallel, inwardly extending annular flanges taking over the opposite faces of the diaphragm. Reference character 16 represents the recording stylus which is mounted in the lower end of an inclined arm or bracket 17, the latter being preferably secured in any suitable manner to the diaphragm 14 at the center and adjacent the edge thereof. The top of the sheet metal diaphragm casing 5 is preferably formed with a central struck-up portion in the form of a dome 18, such portion or dome being provided with a central aperture 19. The diaphragm casing 5 may be conveniently made from sheet metal in the form shown and described by a simple stamping operation.

Reference character 20 represents a hollow, cylindrical, vertically extending tube for operatively connecting the interior of the diaphragm casing 5 with the hollow neck 4. The internal diameter of the tube 20 is approximately equal to the diameter of the opening 19 in the diaphragm casing 5, and the lower end of this tube normally engages and rests upon the top of the diaphragm casing 5 about the opening 19. Preferably, the lower end of the tube 20 is provided with an outstanding annular flange 21 which conforms to the struck-up portion or dome 18 of the diaphragm casing and normally slidably engages the same. The main portion of the upper or outer surface 105 110

of the tube 20 is considerably less in diameter than the bore of the hollow neck 4 into which the tube extends, but the upper end of this tube is flared as indicated at 5 22 so as to fit fairly closely within said bore.

The recording stylus 16 is shown in operative engagement with a cylindrical record tablet 23, and it will be apparent that the position of the diaphragm casing 5 with 10 respect to the body 1, the position of the tube 20 with respect to the hollow neck 4, and also the engagement of the lower end of the tube 20 with the dome 18 of the diaphragm casing, will depend on the thickness 15 of the record tablet 23 and also upon surface irregularities thereof, and will be constantly changing as the recorder is in operation. In order to maintain the tube 20 in operative relation with the interior 20 of the diaphragm casing, with the flange 21 thereof in close, sliding contact with the upper surface of the dome 18, I provide means preferably mounted within the tube 20 and extending through the opening 19 in the diaphragm casing so as to engage beneath 25 the top of such casing. The means I prefer to employ for this purpose consists of a member 24 in the general form of an inverted U, preferably formed of resilient 30 material such as spring wire. The length of the base 25 of the member 24 is slightly greater than the diameter of the bore of the main portion of the tube 20, and when 35 the member 24 is mounted within the tube 20 the base 25 is disposed at the upper flared end 22 of the tube 20. The legs of the member 24 tend to spring apart a distance considerably in excess of that in which they 40 are shown and accordingly when the member 24 is mounted in the tube 20 these legs are under tension and the member 24 is frictionally held in position in the tube 20. The lower end portions 26, 26 of the legs of 45 the member 24 extend laterally toward each other and when the member 24 is mounted in the tube 20 such portions cross each other, as shown, at a point adjacent the lower end 50 of the tube 20 and extend through the opening 19 in the diaphragm casing and beneath the top of said casing so that the ends of the legs lightly and yieldingly engage the under 55 surface of the dome 18. The resiliency of the member 24 permits the same to be readily removed from the tube 20 and inserted therein, and also permits the tube 20 to be 60 readily applied to and removed from operative position with respect to the diaphragm casing 5. When the parts are operatively assembled, however, as shown 65 in the drawing, the member 24 yieldingly maintains the tube 20 in operative relation to the diaphragm casing 5 with the flange 21 closely in engagement with the top of the dome 18 in all operative positions of the 70 diaphragm casing with respect to the body

1. The crossing of the legs of the member 24 at a point adjacent the opening 19 when the parts are in operative position, as shown, is an important feature, for by reason of this the legs of the member 24 will not engage the 75 wall of the opening 19 so as to interfere with the lower flanged end of the tube 20 sliding laterally over the dome 18 as the diaphragm casing 5 moves about the pivot point 7. Consequently, it will be apparent that in all 80 pivotal positions of the diaphragm casing 5 with reference to the body 1 within the operative limits, the flange 21 at the lower end of the tube 20 will be maintained in close contact with the top surface of the dome 18 and the sound waves entering the neck 4 will be effectively conveyed to the interior of the diaphragm casing 5.

I find that by providing the diaphragm casing with the struck-up or upstanding central portion or dome 18, instead of depressing the central portion of the top of said casing so that it lies closely adjacent to the diaphragm, as has heretofore been customary for the purpose of providing a socket for the lower end of the sound-conveying tube, the recorder is rendered more efficient in that the diaphragm is vibrated more truly in accordance with the sound waves transmitted to the recorder, and a more faithful 95 and clearly defined record groove is obtained.

While I have described the preferred embodiment of my invention, it is apparent 100 that the same is subject to many changes and modifications without departure from the spirit of the invention and the scope of the appended claims.

Having now described my invention, what 105 I claim as new and desire to protect by Letters Patent of the United States is as follows:

1. In a device of the class described, the combination with a body portion having an upwardly extending hollow neck, of a diaphragm support movably mounted on said body portion and having an apertured upstanding dome, and a tube the upper end of which extends into said neck and the lower end of which is provided with a flange 110 conforming to and slidably engaging the upper or outer surface of said dome about the aperture therein, substantially as described.

2. In a device of the class described, a diaphragm casing having an aperture in the top thereof, a tube having its lower end engaging the top of said casing about said aperture, and means for holding said tube in operative relation to said casing comprising a member disposed within the tube and having a portion extending through said aperture and beneath the top of said casing, substantially as described.

3. In a device of the class described, a dia-

- phragm casing, the top of which is provided with an aperture, a tube having its lower end engaging the upper surface of the top of said casing about said aperture, and means for holding said tube in operative relation to said casing comprising a resilient member in the general form of an inverted **U**, disposed within said tube and having the lower end portions of its legs extending through said aperture and beneath the top of said casing, the base of said resilient member being of greater length than the diameter of the body portion of said tube and being located at the upper flared end of said tube, substantially as described.
4. In a device of the class described, a diaphragm casing the top of which is provided with an aperture, a tube having its lower end engaging the upper surface of the top of said casing about said aperture, and means for holding said tube in operative relation to said casing comprising a resilient member in the general form of an inverted **U**, disposed within said tube and having the lower end portions of its legs extending through the aperture in said casing and beneath the top of said casing, said lower end portions crossing each other adjacent where they pass through said aperture, substantially as described.
5. In a device of the class described, a diaphragm casing, the top of said casing being formed with an upstanding apertured dome, a tube provided with a flange at its lower end conforming to and slidably engaging the upper surface of said dome about said aperture, and means for holding said tube in operative relation to said casing comprising a member disposed within the tube and having a portion extending through said aperture and beneath the top of said casing, substantially as described.
6. In a device of the class described, a diaphragm casing having an aperture in the top thereof, a tube having its lower end engaging the upper surface of the top of said casing about said aperture, the upper end of said tube being flared, and means for holding said tube in operative relation to said casing comprising a resilient member in the general form of an inverted **U**, disposed within said tube and having the lower end portions of its legs extending through said aperture and beneath the top of said casing, the base of said resilient member being of greater length than the diameter of the body portion of said tube and being located at the upper flared end of said tube, substantially as described.
7. The combination of a diaphragm casing having an aperture in the top thereof, a tube having its lower end engaging the top of said casing about said aperture, and means for holding said tube in operative relation to said casing comprising a substantially **U**-shaped member disposed within said tube and having the end portions of its legs extending through said aperture and beneath the top of said casing, the base of said member being disposed adjacent the top of said tube and being of greater length than the diameter of the main portion of the tube, substantially as described.
8. In a device of the class described, a diaphragm casing formed of sheet metal, the top of said casing being provided with a struck-up or upstanding apertured dome portion, and a tube provided with a flange at one end conforming to and slidably engaging said struck-up portion about the aperture therein, substantially as described.
9. In a device of the class described, a diaphragm casing the top of which is provided with an upstanding apertured dome, a tube having one end conforming to and adapted to slidably engage said dome about the aperture therein, and means for maintaining said end of said tube in operative relation to said casing, substantially as described.

This specification signed this 15th day of February 1921.

FREDERICK P. McINTOSH.

Certificate of Correction.

It is hereby certified that in Letters Patent No. 1,470,633, registered October 16, 1923, upon the application of Frederick P. McIntosh, of East Orange, New Jersey, for an improvement in "Phonograph Recorders," errors appear in the printed specification requiring correction as follows: Page 1, line 109, before the word "same" insert the words *upper or outer surface of the*; page 1, line 110, and page 2, line 1, strike out the words "upper or outer surface of the"; and that the said Letters Patent should be read with these corrections therein that the same may conform to the record of the case in the Patent Office.

Signed and sealed this 27th day of November, A. D., 1923.

[SEAL.]

KARL FENNING,
Acting Commissioner of Patents.
